UNITED STATES PATENT OFFICE.

VILLEROY CORNEY DOUBLEDAY, OF LONDON, ENGLAND.

DEVICE FOR IGNITING SHELL-FUSES.

1,260,287.

Specification of Letters Patent. Patented Mar. 19, 1918.

Original application filed November 27, 1915, Serial No. 63,811. Divided and this application filed February 24, 1917. Serial No. 150,848.

To all whom it may concern:

Be it known that I, VILLEROY CORNEY DOUBLEDAY, a subject of the King of Great Britain, residing at London, England, have invented a new and useful Improved Device for Igniting Shell-Fuses, of which the following is a specification.

This invention relates to an improved device for igniting shell fuses, chiefly applicable to pneumatic guns.

Explosive projectiles which are intended to explode not on impact but after a predetermined period reckoned from the moment at which they are discharged from the gun, usually contain a time fuse which when the propelling force is provided by an explosive, is ignited simultaneously with the explosion of the propelling charge, by the high temperature gases engendered thereby.

Such being absent in pneumatic guns, gas guns and the like, where no explosion but previous compression supplies the propelling force, other means for igniting the time fuses of the shells have to be adopted, and it is the object of this invention to provide reliable, inexpensive and convenient means for this purpose.

These means may however be employed in guns of any kind, irrespectively of the propelling medium and even in guns using high explosives for propelling or throwing projectiles timed to explode at a given moment, variable at will, may form an alternative or additional safeguard for insuring the explosion of the shell charge.

The said means consists broadly in putting an obstacle in the path of the shell either fixedly or detachably arranged on the muzzle of the gun, or in close proximity thereto, which the nose of the shell carrying a detonator strikes and thrusts away; the impact firing the detonator and the latter igniting the time fuse in the usual manner.

In carrying out the invention, for example, by means of a fixed construction, which may be used for a number of consecutive shots, I attach an arm outside the gun muzzle which by means of links, levers and the like holds normally a metal disk, anvil, hammer, weight or the like in the center of the bore close to the muzzle.

Such anvil, disk, block, hammer or the like, may be suitably thickened in the center

and offers a momentary resistance to the impact of the shell nose or its detonator and is then violently flung aside, the shock being partly or wholly taken up by link-work and the like, preferably by spring joints, helical screws, inclines or the like, so that the disk or weight may return by gravity, spring power or the like to its normal position.

In the preferred form however, the obstacle is detachably slipped on the muzzle and held by wire, strips of metal or the like and lost with each shot, being of so inexpensive a nature that this does not matter.

In the accompanying drawing:—

Figures 1, 2 and 3 show views of a convenient form of obstacle support carried out in sheet iron, and

Figs. 4, 5 and 6 show a similar support made from wire, both forms supporting a disk or the like having sufficient inertia to operate on impact a detonating device provided on or protruding from within the nose of the shell.

The obstacle 18 shown in section in Fig. 1 has a groove 19 to receive prongs 20 of a carrier clip 21, Figs. 2 and 3, forced over one shoulder 22 of the obstacle, and this clip has claws 23 adapted to clasp the muzzle 30 of a gun.

Instead of this arrangement, a wire frame or wire coils 26 may be employed to hold the obstacle centrally relatively to the muzzle 30 as shown in Figs. 4, 5 and 6, where wire arms 31 partly or wholly encircle the obstacle. The wire arms being partly coiled around the groove 19, allow of being closed up, as in Fig. 4, conveniently for transport.

As a shell leaves the muzzle of the gun, it strikes the obstacle 18 whereby the shell detonating device carried at the nose of the shell (not shown) is caused to ignite the time fuse.

The projectile will not be deflected by striking against the obstacle because the impact takes place while the body of the shell is still guided within the bore of the gun barrel.

I claim:

1. A shell detonating device comprising an obstacle, and means for supporting the obstacle at the muzzle of a gun.
2. A shell detonating device comprising a grooved obstacle and a carrier having a

part rotatable within the groove in the obstacle, and clips extending outwardly therefrom.

3. A shell detonating device comprising a grooved obstacle, and a carrier clip provided with prongs lodged in the groove in the obstacle.

4. A shell detonating device comprising

a grooved obstacle, a carrier clip, prongs on said clip lodged in the groove in the obstacle, and claws extending from the clip.

VILLEROY CORNEY DOUBLEDAY.
